DESIGN FOR A PRESS FRAME

George E. Munschauer, Buffalo, N. Y.

Application September 22, 1938, Serial No. 80,044

Term of patent 7 years

To all whom it may concern:

Be it known that I, George E. Munschauer, a citizen of the United States, residing at Buffalo, in the county of Erie and State of New York, have invented a new, original, and ornamental Design for a Press Frame, of which the following is a specification, reference being had to the accompanying drawing, forming a part thereof.

Fig. 1 is a perspective view of a press frame showing my new design;

Fig. 2 is a top plan view of the design shown in Fig. 1; and

Fig. 3 is a bottom plan of the design shown in Fig. 1.

I claim:

The ornamental design for a press frame, as shown.

GEORGE E. MUNSCHAUER.
